UNITED STATES PATENT OFFICE.

WILLIAM JESSE MORRIS, OF RECTOR, ARKANSAS.

RAILWAY DRAFT-GEAR.

1,193,288.

Specification of Letters Patent.

Patented Aug. 1, 1916.

Application filed January 19, 1916. Serial No. 73,000.

To all whom it may concern:

Be it known that I, WILLIAM J. MORRIS, a citizen of the United States, residing at Rector, in the county of Clay and State of Arkansas, have invented certain new and useful Improvements in Railway Draft Gears, of which the following is a specification, reference being had to the accompanying drawings.

10 This invention relates to an improved railway draft gear and has for its primary object to provide a draft gear or rigging which is so constructed that should any part of the gear be accidentally broken, the cars 15 or coaches will be automatically uncoupled, thus obviating possibility of damage to the cars and injury to the passengers.

It is another and more particular object of the invention to provide a railway draft 20 gear embodying a draft head, draft bars and means connecting the same to the head, a guide plate for the draft head suspended from the car sills and preventing the displacement of the connecting means, a central gear box or frame, and cushioning 25 means for the draft bars arranged therein, said draft head moving longitudinally when the draw bar or gear box is broken so that the connecting means between the bar and 30 head will be disposed at one side of the guide plate and will fall by gravity, thus disconnecting the bar and head from each other.

It is an additional object of the invention 35 to provide a draft rigging or gear which is simple and durable in its construction and may be readily applied to railroad cars or coaches at nominal cost and without necessitating any material alterations therein.

40 With the above and other objects in view, my invention consists in the novel features of construction, combination and arrangement of parts to be hereinafter more fully described, claimed and illustrated in the accompanying drawing, in which,

Figure 1 is a side elevation illustrating the preferred embodiment of my improved draft gear, one of the draw bars and heads being shown in section; Fig. 2 is an enlarged 50 vertical sectional view; and Fig. 3 is a transverse section taken on the line 3—3 of Fig. 2.

Referring in detail to the drawing, 5 designates the car which is provided with spaced longitudinally extending sills 6. The draw head 7 is formed on the rear end

of the coupling member 8 which is suspended from the end of the car body by chains, indicated at 9. This draw head is of rectangular form. On the top of the draw head, an abutment 10 is formed for bearing engagement against the transverse end bar of the car frame.

11 designates the elongated gear box which is centrally disposed between the parallel sills 6. This box is provided with detachable top and bottom plates 12 formed upon their ends with the angular flanges 13 which are provided with openings to receive the connecting or clamping bolts 14 extending vertically across the ends of the box 11. Each of the end walls of the gear box is provided with a rectangular opening through which the movable draw bar 15 extends. One end of this draw bar is enlarged, as shown at 16, and fits within the draw head 7, the said enlarged end of the bar being provided with a tapering opening 17 which coincides with similar openings 18 provided in the top and bottom walls of the draw head. The openings 17 and 18 receive a frusto-conical plug 19 which is inserted upwardly through said openings.

20 designates a guide or supporting plate upon which the draw head moves. This plate is suspended by vertical rods or bolts 21 connected to the corners thereof, from the sill bars 6.

A washer plate 22 of rectangular form is arranged upon each of the draw bars 15 within each end of the gear box 11. This washer plate is provided upon one face with parallel flanges 23 for engagement in grooves or channels cut in the inner face of the end wall of the gear box. Upon the draw bar 15, a coil spring 24 is arranged and this spring is surrounded by a relatively large coil spring 25. These springs bear at their outer ends against the washer plate 22 and at their inner ends against a plate 26 on the end of the draw bar. A nut 27 is threaded upon the end of the draw bar and a key 28 is engaged through an opening in the end of the draw bar to retain the nut in place thereon. The gear box 11 is supported by a transverse bar or plate 29 which is suspended from the sills 6 by the vertical rods or bolts 30.

From the above description, taken in connection with the accompanying drawing, the construction and manner of operation of the

invention will be fully understood. Normally, the abutment lugs 10 bear against the ends of the car or coach and prevent the inward movement of the draw head. In the 5 relative movement of the cars, the springs 24 and 25 act to yieldingly limit and cushion the movement of the draw bars. These springs are of such tension however, that this relative movement is in no case great enough to permit the larger lower end of the connecting plug 19 to move off of the 10 plate 20. Therefore, in the operation of the device, the draw heads of the several cars in the train will remain positively connected to each other. Should one of the 15 draw bars break or become disengaged from the gear box from any cause, the forward car will pull ahead and move the draw head connected to the next car in the rear forwardly, so that the plug 19 will be disposed in advance of the plate 20. This plug which is constructed of solid metal, will drop downwardly through the openings 17 and 18 and thus disconnect the draw bar 20 from the draw head and permit the cars to 25 separate. In this manner, all liability of damage to the cars or injury to the passengers is obviated in the event of breakage of the draft gear or rigging.

30 The invention, as illustrated, consists of few elements of simple form which are reliable and positive in their action.

It is apparent that the device is not limited to the particular form or construction of 25 the gear box, draw bar or draw head as

shown, and that the principle employed may also be utilized in connection with various other constructions of these parts.

The invention is also susceptible of a great many modifications in the form, proportion and arrangement of its detail structural features, and I, therefore, reserve the privilege of adopting all such legitimate changes as may be fairly embodied within the spirit and scope of the invention as 45 claimed.

Having thus fully described my invention, what I desire to claim and secure by Letters Patent is:—

A railway draft gear including a gear box and draw head, a draw bar yieldably connected at one end to the gear box, a plate suspended upon the car from which the draw head is slidably supported, said draw bar and head having coinciding tapering 50 openings, a conical-shaped pin adapted to be inserted upwardly through said openings and normally held against displacement by said guide plate, said pin being moved with relation to said plate upon an excessive 55 movement of the draw head whereby the pin may gravitate downwardly and disconnect the draw bar from the draw head.

In testimony whereof I hereunto affix my signature in the presence of two witnesses. 60

WILLIAM JESSE MORRIS.
